UNITED STATES PATENT OFFICE.

ALEXANDER T. KASLEY, OF ESSINGTON, PENNSYLVANIA, ASSIGNOR TO WESTINGHOUSE ELECTRIC AND MANUFACTURING COMPANY, A CORPORATION OF PENNSYLVANIA.

TURBINE.

Application filed April 12, 1923. Serial No. 631,672.

My invention relates to turbines, more particularly to those of the marine type, and it has for its object to provide apparatus of the character designated which shall 5 have means to oppose the pumping action of ahead blading and possible consequent breakage thereof when the reversing blading is in operation.

Trouble has been encountered on account 10 of the breakage of ahead marine turbine blading of the reaction type, particularly when rotating idly with the astern blading in operation. Since breakage has occurred safely within the allowable centrifugal 15 stresses of the ahead blading, such breakage is apparently due to induced vibrations of fluid set up in the ahead blading incident to astern operation. This is further shown by the fact that breakage has occurred from the 20 last row of reaction blading well back toward the high-pressure end and including some of the shorter blading.

It is well known that, if reaction blading is operated backwards, it develops a pumping 25 action or acts as a compressor. With the inlet end of ahead blading of this type closed, reverse operation thereof results in the development of fluctuating pressures or 30 pressure waves whose frequency is dependent upon the turbine speed. If these pressure waves or fluid vibrations or some higher harmonics thereof are resonant with the natural 35 period of any of the blading, then a condition of resonance may take place, resulting in excessive amplitudes of vibration 40 of such blading and possible breakage thereof. The natural frequency of the reaction blading increases as they become shorter. Hence, when the astern or reversing section 45 is operated, pressure waves or fluid vibrations, due to the pumping action of the ahead reaction blading and having a frequency dependent upon the speed, change in frequency as the speed increases; and, when 50 the fluid vibrations or pressure waves or their harmonics are resonant with the natural period of any of the blades, dangerous vibrations of the latter may be set up. As the reversing speed is changed, resonance 55 may occur with successive rows of shorter blading, thereby explaining the breakage of reaction blading of a large part of the turbine as already referred to.

Accordingly, it is the object of my invention to provide means to supply steam to

the inlet end of the ahead blading, whenever the astern blading is in operation, to secure such a speed of flow as to minimize or eliminate the development of pressure waves of fluid and consequent resonant vibration of 60 the blading and breakage of the latter.

Apparatus made in accordance with my invention is illustrated in the accompanying drawings, forming a part of this application, in which Fig. 1 is a diagrammatic 65 view showing a marine turbine installation with my improvement applied thereto; and Fig. 2 is a detail view showing valves in section used in Fig. 1.

Referring now to the drawings for a better 70 understanding of my invention, in Fig. 1, I show a turbine having an ahead section 30, and a reversing or astern section 31. Steam is supplied to the ahead section 30 by any suitable conduit or passage 32, including a valve 34. In like manner steam is supplied to the reversing section 31 by a 75 conduit 33 having a valve 35.

With the structure described, when the reversing section 31 is in operation the reaction blading 37 of the ahead section 30 develops a pumping action and consequent pressure waves or vibrations in the fluid. As already pointed out, if such pressure waves should be resonant with the natural 80 period of any of the blades, dangerous vibrations and possibly breakage of the latter might occur. I therefore provide means, in connection with an arrangement of this character, which shall assure opposition to 85 the development of pressure waves whenever the reversing section is in operation.

The means referred to comprises a conduit 36 connected to the inlet of the reversing section 31, and to the inlet of the ahead 90 section 30. This conduit or passage includes a check valve 28 which opens in the direction of the inlet of the ahead section 30, and closes in the other direction. The check valve therefore serves to prevent by-passing 95 of any of the steam from the ahead section when the latter is in operation. However, when the reversing section 31 is in operation, some of the steam passing through the valve 35 passes through the conduit 36 and 100 enters at the inlet end of the ahead section 30, passing through the reaction blading 37 of said section. The pressure of steam passing 105 through the conduit 36 and the volume thereof are sufficient to develop a counter- 110

flow through the ahead section which shall effectively oppose a pumping action and consequent pressure of waves and resonant vibration of the reaction blading 37.

5. It is desirable that the minimum quantity of steam shall be used for the purpose of opposing the pumping action. I, therefore, show a throttle valve 29 in the conduit 27 which may be permanently set to supply just 10 enough steam for the purpose stated. The direction of flow through the conduit 27 to minimize pumping effects of the reaction blading is indicated by the arrows in Fig. 1. An example of check and throttle valves 15 suitable for my purpose more clearly appear in Fig. 2.

From the foregoing description, the operation of apparatus made in accordance with my invention will be obvious. Steam is supplied from any suitable source to the ahead reaction blading in order to oppose the pumping action and consequent resonant vibration of such blading whenever the astern section is in operation.

25. While I have shown my invention in but two forms, it will be obvious to those skilled in the art that it is not so limited, but is susceptible of various other changes and modifications without departing from the spirit 30 thereof, and I desire, therefore, that only such limitations shall be placed thereupon as are imposed by the prior art or as are specifically set forth in the appended claims.

What I claim is:

1. In a turbine installation, an ahead section which develops a pumping action when operating reversely, a reversing section, a conduit between the inlet ends of said sections, and a check valve in the conduit which opens in the direction of the inlet end of the ahead section, whereby, when the reversing section is in operation, steam is also supplied to the inlet end of the ahead section. 35

2. In a turbine installation, an ahead section including reaction blading, a reversing section, a conduit between the inlet ends of said sections, and a check valve in the conduit opening in the direction of the inlet end of the ahead section, whereby, when the reversing section is in operation, steam is supplied to the inlet end of the reaction blading 40 of the ahead section. 45

3. In a turbine installation, an ahead section including reaction blading, a reversing section, a conduit between the inlet ends of said sections, a check valve in the conduit opening in the direction of the inlet end of the ahead section, whereby, when the reversing section is in operation, steam is supplied to the inlet end of the reaction blading, 50 and an adjustable throttle valve in the conduit for regulating the rate of flow therethrough. 55

In testimony whereof, I have hereunto subscribed my name this 9th day of April, 1923.

ALEXANDER T. KASLEY.
